UNITED STATES PATENT OFFICE

FREDERICK S. MCCULLOUGH, OF WILKINSBURG, PENNSYLVANIA, ASSIGNOR TO WESTINGHOUSE ELECTRIC & MANUFACTURING COMPANY, A CORPORATION OF PENNSYLVANIA

VACUUM TUBE FILAMENT STRUCTURE

Application filed September 16, 1922, Serial No. 588,558. Renewed November 9, 1928.

My invention relates to evacuated electric devices, having particular relation to the cathode structures of such devices.

An object of my invention is to provide a cathode especially designed for use in power tubes which is of unusual rigidity and strength of construction and which lends itself to inexpensive quantity-production methods of manufacture.

10 Another object of my invention is to provide a cathode, whereby a thin, fragile, oxide-coated element may be employed in high-voltage, high-power tubes, wherein heavy electrostatic forces obtain between the cathode and the other elements of the tube.

Another object of my invention is to provide a cathode of improved design, whereby heavy electron emissions may be obtained with extremely low energizing currents.

20 In the construction and operation of a power tube, it has, heretofore, been customary to employ a single electron-emitting element which may or may not be provided with an oxide coating. In order to obtain the necessary electron emission from a cathode of the above-mentioned character, it has been necessary to operate the same at as high temperatures as possible, thereby necessitating a heavy exciting current, and greatly 30 shortening the life of the tube.

According to my invention, I provide a cathode embodying a construction for carrying the above indicated desired results into effect. Very briefly, the cathode comprises 35 a supporting element and a fragile, oxide-coated element which is wound around said supporting element and supported thereby.

With these and other objects in view, my invention further consists in the details of 40 construction and arrangement hereinafter described and claimed, and illustrated in the accompanying drawing, wherein

45 Figure 1 is a front elevational view, shown partially in section, of a vacuum-tube device embodying my invention; and

Fig. 2 is an enlarged detail view of the cathode construction embodying my invention, with the oxide-coated element partly unwound from the supporting element.

50 In the illustrated embodiment of my inven-

tion shown in the drawing, an evacuated electric device 1 is provided in the form of an elongated tube having one end provided with a re-entrant portion 3 terminating in a supporting press 4. A cathode element 6 embodying my invention is positioned in the axis of the tube 2 and has its opposite ends supported by carrier rods 7 and 8 which are mounted in the press 4. The carrier rods 7 and 8 may be extended through the press 4 by means of external connections 9 and 11, which are electrically connected thereto.

A helical grid element 12 is symmetrically disposed about the cathode 6 and may be supported by means of a carrier rod 13 which is mounted in the press 4. The carrier rod 13 may be extended through the press 4 by means of a connection 14 to provide an external connection for the grid 12.

A cylindrical anode element 15 is symmetrically disposed with respect to the aforementioned elements and is supported by carrier rods 16 and 17 which are also mounted in the press 4. One of the carrier rods, as 16, may be extended through the press 4 to provide an external connection 17a for the anode 15.

The cathode structure 6 comprises a central core member or rod 18 and a fragile oxide-coated metallic strip 19, which is spirally wound around the core member 18 and supported thereby. Adjacent ends of the core member 18 and of the strip 19 are welded together near the connection with the supporting rod, thereby connecting the core 18 and the strip 19 in parallel relation at opposite ends.

The central core 18 may be of any material which is easily degasified and which is capable of withstanding the heavy electrostatic forces peculiar to power-tube constructions. In actual practice, I have found that a rod of tungsten is very satisfactory. The fragile metallic strip 19 may correspond in strength to the cathode elements of small receiving tubes wherein a thin strip of platinum iridium having an oxide coating is usually employed. It is noted that the different elements or sections constituting the cathode structure 6 have different emissivities. The

strip has a higher specific resistance than the rod of tungsten.

The core member 18 is so designed that, when the fragile metallic strip 19 is heated 5 to its normal operating temperature, the temperature of the rod 18, caused by the heating effect of the currents passing therethrough, will correspond to that of the metallic strip 19, thereby preventing a transfer of heat from the strip 19 to the rod 18.

As previously pointed out, one advantage of my invention is the provision of a cathode of simple but rugged construction which is especially well adapted for high-power 15 transmitting tubes employed in wireless-transmission systems. Another advantage of my invention is the provision of a cathode requiring extremely small energizing currents to provide the necessary plate-filament 20 currents.

While I have shown only one embodiment of my invention in the accompanying drawing, it is capable of various changes and modifications without departing from the 25 spirit thereof and I desire that only such limitations shall be imposed thereon as are specifically set forth in the appended claims or demanded by the prior art.

I claim as my invention:

30 1. A filamentary member comprising a conductive supporting rod and a relatively fragile oxide-coated strip having a higher specific resistance wrapped therearound, the relative conductivities and dimensions of 35 said rod and said strip being such that when they are energized in parallel the rod shall be heated to a temperature not substantially lower than the temperature of said electron-emitting element when the latter is heated to 40 thermionic activity.

2. A cathode structure for use in electric-discharge devices comprising a tungsten rod and a relatively fragile conducting strip wrapped therearound, the said strip being 45 thermionically active at a lower temperature than the supporting rod, the relative conductivities and dimensions of said rod and strip being such that, upon being energized in parallel, the rod shall be heated to a temperature not substantially lower than the temperature of said strip when the latter is heated 50 to thermionic activity, whereby electrons emitted from said cathode structure, when energized, are predominately from said strip and heat does not flow from said strip to said rod.

3. A cathode structure for use in electric-discharge devices comprising a conductive rod and a relatively fragile conducting ribbon so wrapped therearound that the edges of said strip are in contact with one another throughout the helix formed thereby, the said ribbon comprising a material that is thermionically active at a lower temperature 60 than the supporting rod, and the relative

conductivities and dimensions of said rod and strip being such that, upon being energized in parallel, the rod shall be heated to a temperature not substantially lower than the temperature of said strip when the latter is 70 heated to thermionic activity.

4. A cathode structure for use in electric-discharge devices comprising a supporting core and a relatively fragile conducting strip having a higher specific resistance wrapped 75 therearound, said conducting strip being capable of emitting electrons at a lower temperature than said core, and the relative conductivities and dimensions of said core and said strip being so related that, when they are connected in parallel to a suitable potential source, the rod shall be heated to a temperature that is substantially the same as the temperature of said strip when the latter is 80 heated to thermionic activity.

5. A cathode structure for use in electron-discharge devices comprising an electrically-conducting heating element, an electrically-conducting strip of higher specific resistance wrapped upon said element, a material of 85 lower conductivity than either said element or said strip, said material being located between, and in contact with, said element and said strip, said element and said strip being 90 electrically connected in parallel.

6. A cathode structure for use in electron-discharge devices comprising an electrically-conducting heating element, and an electrically-conducting strip of higher specific resistance wrapped upon said element, a material of lower conductivity than either said element or said strip, said material being positioned in the form of a coating around said strip and comprising an oxide which is thermionically active at a lower temperature than 100 either said element or said strip.

7. A cathode structure for use in electron-discharge devices comprising an electrically-conducting heating element, and an electrically-conducting strip of higher specific resistance wrapped upon said element, a material of lower conductivity than either said element or said strip, said material being located between, and in contact with, said element and said strip and comprising a layer 110 of thermionically emissive oxide.

8. A cathode structure for use in electron-discharge devices comprising an electrically-conducting supporting and heating rod, an electrically-conducting element of higher 120 specific resistance surrounding said rod, a coating of material surrounding said electrically-conducting element, said material having a lower conductivity than either said rod or said electrical-conducting element and being thermionically active at a lower temperature than either said rod or said electrically-conducting element.

9. An incandescent cathode comprising a core of highly refractory metal, a metal wire 130

helically wound on the said core so as to be in electrical contact therewith, and a substance of high electron emitting capacity applied to said wire.

5 10. An incandescent cathode, comprising a core consisting of tungsten, a metal wire helically wound on the core so as to be in electrical contact therewith, and a substance of high electron emitting capacity comprising an oxide applied to said wire.

10 11. An incandescent cathode comprising a core consisting of tungsten, a metal wire comprising platinum helically wound on the core so as to be in electrical contact there-

15 with, and a substance of high electron emitting capacity comprising an oxide applied to said wire.

12. An incandescent cathode comprising a core consisting of tungsten, a platinum wire

70

helically wound on the core so as to be in electrical contact therewith, and a substance of high electron emitting capacity comprising an oxide applied to said wire.

In testimony whereof, I have hereunto sub- 75
scribed my name this 12th day of September,
1922.

FREDERICK S. McCULLOUGH.
